(21) Appl. No.: **29/174,090**

Primary Examiner—Charles A. Rademaker

(22) Filed: **Jan. 9, 2003**

CLAIM

(51) LOC (7) Cl. **14-03**

The ornamental design for a network system coupling case, as shown and described.

(52) U.S. Cl. **D14/242**

DESCRIPTION

(58) Field of Search **D14/240, 242,**

FIG. 1 is a perspective view of a network system coupling case showing my new design;

D14/353, 299, 433, 256; 379/440, 93.09,
93.08, 93.15, 93.16, 165; D13/184, 152;
361/622; 45/500-556; 375/200-225

FIG. 2 is a front elevational view thereof;

(56) References Cited

FIG. 3 is a rear elevational view thereof;

U.S. PATENT DOCUMENTS

FIG. 4 is a top plan view thereof;

D263,957 S * 4/1982 **Pemberton** **D14/356**
D346,606 S * 5/1994 **Harris et al.** **D14/242**
D351,601 S * 10/1994 **Rak** **D14/242**
D363,722 S * 10/1995 **Aldridge et al.** **D14/242**

FIG. 5 is a bottom plan view thereof;

FIG. 6 is a left side elevational view thereof; and,

FIG. 7 is a right side elevational view thereof.
